(No Model.)

N. G. MOONEY.
HOOF PAD.

No. 576,320.

Patented Feb. 2, 1897.

UNITED STATES PATENT OFFICE.

NICHOLAS G. MOONEY, OF SING SING, NEW YORK.

HOOF-PAD.

SPECIFICATION forming part of Letters Patent No. 576,320, dated February 2, 1897.

Application filed November 13, 1896. Serial No. 611,984. (No model.)

To all whom it may concern:

Be it known that I, NICHOLAS G. MOONEY, a citizen of the United States, residing at Sing Sing, in the county of Westchester and 5 State of New York, have invented certain new and useful Improvements in Hoof-Pads, of which the following is a specification.

This invention relates to a pad for the hoofs of horses and other draft-animals, and is used 10 in connection with the short or calkless shoes with the object of giving the horse's hoof a better hold on asphalt or slippery streets during winter.

To these ends my invention consists of a 15 hoof-pad which comprises an elastic cushion provided with an inwardly-projecting portion and with tapering forwardly-extending tongues or fins and also with tapering strengthening-ribs extending from the inner 20 corners of the cushion along the inner edges of said tongues or fins and a superposed sole-plate of horseshoe shape connected at its rear 25 ends by a transverse connecting-piece, whereby a central opening conforming to the interior 30 space of the hoof is provided, said sole-plate being stitched or otherwise suitably fastened to the cushion and its fins.

In the accompanying drawings, Figure 1 is 35 a side elevation showing my hoof-pad used in connection with a calkless shoe and applied to a horse's hoof. Fig. 2 is an enlarged under side view of the same, portions of the shoe and sole-plate being broken away; and Fig. 3 is a section on line 3 3, Fig. 2.

Similar letters of reference indicate corresponding parts.

Referring to the drawings, A represents the well-known calkless and heelless shoe in connection with which my improved hoof-pad is 40 used.

The main elements of my hoof-pad are an elastic cushion B and a sole plate or layer C, superposed above the elastic cushion B and sewed to or connected thereto in any 45 suitable manner. The cushion B is made quite thick at the point where it is applied back of the shoe under the posterior portion of the hoof and is formed with a projecting center portion b, which extends partly over 50 the frog of the hoof, so as to give a bearing to the same. The cushion B is substantially U-shaped, the thickened transverse main por-

tion or body of which is provided with forwardly-projecting tongues or fins b', formed by recessing the side portions of the cushion, 55 said recesses receiving the end portions of the calkless shoe A, while the fins b' of the elastic body are superposed above the shoe and constitute an elastic filling-layer between the shoe and the sole piece or plate C. The recesses do not extend entirely across the side 60 portions of the cushion, but terminate a short distance from the inner edges of the said side portions, so as to provide gradually-tapering strengthening-ribs or filling-pieces b², which 65 extend along the inner edges of the shoe or the hoof when the latter is applied to the pad.

While the main body B of the cushion furnishes the antislipping portion of the device, the thin interposed tongues or fins b' afford 70 a cushion for the rear ends of the shoe, so that there is a certain degree of elasticity presented to the said rear ends. The sole-plate C conforms in shape to the hoof and is made slightly wider than the shoe A and connected 75 at its rear ends by a bridge-piece C', that conforms to the shape of the cushion proper and has an opening d below the hoof. This sole-plate C is either made of leather of suitable thickness or of a layer of leather, an intermediate layer of cork or other suitable material, and a top layer of felt or like moisture-retaining substance.

The object in providing an opening in the sole-plate C is to permit air to freely circulate underneath the hoof of the shod animal and, furthermore, to prevent the rotting of the hoof, as is always the case where said sole-plate is imperforate or is provided with no central opening.

My improved hoof-pad has the advantage that it furnishes a good foothold for the horse on asphalt or other slippery streets and permits at the same time free access of air to the hoof, so as to prevent diseases of the foot due 95 to the exclusion of the air.

Having thus described my invention, I claim as new and desire to secure by Letters Patent—

1. A hoof-pad, consisting of an elastic cushion of U shape, the connecting portion of which is much thicker than the side portions, said side portions being recessed to form tongues or fins at the upper surface of the

cushion, and a sole-plate secured to the cushion and provided with a central opening conforming nearly in size to the space within the shoe, substantially as set forth.

5 2. A hoof-pad, consisting of an elastic cushion thickened at its rear part and provided with tapering forwardly-extending tongues or fins, and with tapering ribs at the inner edges of the said tongues or fins, and a sole-
10 plate attached to the cushion and provided

with a central opening, substantially as set forth.

In testimony that I claim the foregoing as my invention I have signed my name in presence of two subscribing witnesses.

NICHOLAS G. MOONEY.
